UNITED STATES PATENT OFFICE.

WILLIAM G. SHELTON, OF ST. LOUIS, MISSOURI.

HAIR WINDER.

Application filed September 3, 1927. Serial No. 217,351.

My invention relates to apparatus used in hair curling and waving operations and consists in a mechanical hair wrapping device.

5 The main object of my invention is to provide a device which will enable an operator to wrap a strand of hair firmly, evenly, and closely on a curling rod.

Incidental objects are to provide for a 10 quick and simple application of the strand of hair to the device; to provide an economical device for the purpose intended; and to provide a device which is adapted for use with various curling rods irrespective of 15 the diameter of the latter.

In the accompanying drawings which illustrate a selected embodiment of my invention—

Figure 1 is a top view of my device showing the same assembled with a curling rod to which a strand of hair is attached.

Figure 2 is a side elevation of the same.

Figures 3 and 4 are sections taken on the line 4—4 of Figure 1 and show one of the 25 parts illustrated in two different positions.

Figure 5 is a section taken on line 5—5 of Figure 1 with one of the elements rotated from the position shown in Figure 1.

My device comprises a base 1 which preferably is formed of hard rubber or other insulating material and near the forward end of this base is an upstanding stud 2, the sides of which are preferably tapered from the base outwardly and the stud terminates in an overhanging shoulder 3. Near the opposite end of the base is a pivoted clip 4 having a pair of jaws 5. A barrel-like member 6, having an open side, is slidably and rotatably mounted in the jaws 5 and extends therefrom forwardly of the base alongside of stud 2. A spring 7 is secured to the base and has an upstanding arm 8 extending through a slot 9 in the base and adapted to engage the side of barrel 6 which faces away from stud 2. The forward end of barrel 6 is provided with peripherally extending slots 10 which are adapted to receive spring arm 8 when the barrel is turned to the position shown in Figure 4. This permits the spring arm to engage the strand of hair in the barrel and the pressure of the spring on the strand of hair will cause the latter to wrap more tightly on the curling rod 11. This curling rod may be of any ordinary type and is in-

serted between stud 3 and barrel 6 and is yieldingly gripped between these two elements by the action of spring 7.

A strand of hair 12 is tied in the usual manner near the customer's scalp by a cord 13 and the strand is secured to the end of curling rod 11 in the usual manner. The strand of hair is then laid into the trough formed by the barrel member 6, the strand passing through the opening between jaws 5. The barrel 6 is then rotated on its axis from the position shown in Figure 3 to the position shown in Figure 4, in which the strand of hair is retained in the barrel by spring arm 8 and by the outer jaw 5.

70 The device, including base 1, stud 3, and barrel 6, may now be rotated as a unit about the rod 11 and the strand of hair will be wrapped about the rod and as the strand of hair is wrapped it will gradually feed 75 the rod 11 longitudinally of the device.

Obviously the spring pressure on the strand of hair and the pressure on the rod can be adjusted so that the proper tension will be placed on the hair and rod and the 80 tension on the hair and the tightness of the coils need not be left to the operator. In order to flatten the strand of hair and also to enable the use of a larger trough member than would otherwise be practical, I fill the bottom of the trough as indicated at 14. The inner face of this filler being flat cooperates with the substantially straight spring portion 8 to shape the hair strand to a flat section as the latter is wrapped about 85 the curling rod.

The shape of the upstanding stud 2 tends to force the rod down against the base and this downward pressure on the curling rod is augmented by making the barrel member 6 of larger diameter than the curling rod so that the member 6 engages the curling rod above the diametrical line of the latter which is parallel with the base. Preferably the pivoted end of clip 4 is provided with 90 an upwardly curved extension 15 which engages the curling rod similarly to the engagement by stud 2 and tends to hold the parts in desired assembled relation.

When the strand of hair has been wrapped 105 it is tied at the outer end in the usual manner and the wrapping device slips off the end of the rod without the necessity of removing or releasing any parts.

Obviously the details of my invention may 110

be modified without departing from the spirit of my invention, and I contemplate the exclusive use of such variations in my device as come within the scope of my claims.

5. I claim:

1. In a hair wrapping device, a base, an upstanding shoulder thereon, a hair receiving container rotatably mounted in said base, means yieldingly moving said container toward said shoulder, there being space between said container and shoulder adapted to receive a curling rod about which the hair is wrapped.

2. In a hair wrapping device, a base, an upstanding shoulder thereon, a trough-like element rotatably mounted on said base and extending alongside of said shoulder and adapted to receive a strand of hair transversely of its axis.

20. 3. In a hair wrapping device, a base, a hair receiving trough pivotally mounted on said base and rotatable on its axis, an element on said base spaced from the pivotal mounting of said trough and converging outwardly from said base toward the side of said trough, a curling rod extending between said element and said trough, and means pressing said element and trough toward each other to yieldingly engage said rod between them.

25. 4. In a hair wrapping device, a base, an upstanding shoulder thereon, a clip pivotally mounted on said base at a point spaced a substantial distance from said shoulder and having a pair of opposed jaws, an elongated hair receiving trough rotatably mounted in said jaws and extending past said shoulders, and a spring for pressing said trough and shoulder toward each other.

30. 5. In a hair wrapping device, a base, an upstanding shoulder thereon, a clip pivotally mounted on said base at a point spaced a substantial distance from said shoulder and having a pair of opposed jaws, an elongated hair receiving trough rotatably mounted in said jaws and extending past said shoulders and provided with opposed slots extending peripherally, and a spring engaging the side of said trough facing away from said shoulder, said spring being adapted to enter said slots when said trough is rotated in said jaws.

6. In a hair wrapping device, a base, an

upstanding shoulder thereon, a hair receiving trough-like member rotatably mounted on said base and movable to and from said shoulder, a spring on said base pressing said member toward said shoulder, there being a recess in the side of said member for receiving said spring transversely of said member so as to engage the hair therein when said member is rotated to a predetermined position.

7. In a hair wrapping device, a base, an upstanding shoulder thereon, a hair receiving trough-like member rotatably mounted on said base and movable to and from said shoulder, the inner bottom of said member being filled in and flattened, a spring on said base pressing said member toward said shoulder and including a substantially straight element adapted to oppose the inner bottom of said member and cooperating therewith in flattening a strand of hair contained in said member.

8. In a hair wrapping device, a hair receiving member having an open side through which a strand of hair may be passed transversely of its length, means for holding the strand of hair in said member, and means for mounting a curling rod adjacent to the end of said member so that said member and rod may be rotated about each other.

9. In a hair wrapping device, a base, a curling rod extending longitudinally of said base, elements on said base spaced longitudinally of said rod and adapted to engage opposite sides thereof, a trough-like member extending longitudinally of said base and adapted to receive a strand of hair and to engage a side of said rod opposite to one of said elements.

10. In a hair wrapping device, a base, a curling rod extending longitudinally of said base, elements on said base spaced longitudinally of said rod and adapted to engage opposite sides thereof, a trough-like member extending longitudinally of said base and adapted to receive a strand of hair and to engage a side of said rod opposite to one of said elements at least one of said elements and said member being shaped so as to press said rod against said base.

In testimony whereof I hereunto affix my signature this 27th day of August, 1927.

WILLIAM G. SHELTON.
